UNITED STATES PATENT OFFICE.

FREDERICK J. BANCROFT, OF PAWTUCKET, RHODE ISLAND.

TENNIS-RACKET.

1,166,340.

Specification of Letters Patent. Patented Oct. 12, 1915.

Application filed July 7, 1915. Serial No. 38,415.

To all whom it may concern:

Be it known that I, FREDERICK J. BANCROFT, a citizen of the United States, residing at Pawtucket, in the county of Providence and State of Rhode Island, have invented certain new and useful Improvements in Tennis-Rackets, of which the following is a specification.

My invention relates to rackets, bats, and 10 similar game implements.

The essential objects of my invention is to prolong the life of this type of implement the breakage of which is now usually due to excessive vibration; to insure at the 15 same time such an elasticity or resiliency of the frame as to furnish a spring or "kick"; to increase the strength of the structure and to attain these objects in a structure which is properly balanced, symmetrical, light and 20 inexpensive.

To the above ends essentially my invention consists in such parts and combinations of parts as fall within the scope of the appended claims.

25 In the accompanying drawings which form a part of this specification, Figures 1 and 2 are front and side elevations respectively of a tennis racket embodying my invention, and Figs. 3 and 4, sections on lines 30 3—3 and 4—4 of Fig. 1 respectively.

Like reference characters indicate like parts throughout the views.

My racket comprises a bow A, a net B, and handle C. The constituent outer and 35 inner wooden strips d and e of the bow, which converge downwardly in the usual manner to form the handle, have interposed between them a strip of raw hide f extending throughout the extent of the bow and 40 extending some distance into the handle. The strip f is engaged by glue and attached by the catgut or filling B to the adjacent strips. The layer or filling f is tough and unbreakable, and stronger than iron, particularly in a structure like the present 45 wherein it is subjected to vibration. I have found that raw hide will resist successfully the effects of a vibration sufficient to crystallize metal rivets. The strip f, however, being comparatively thin permits an action of 50 the parts necessary to afford a resiliency effect upon a ball, and lends a maximum of strength to the structure.

The throat piece or crotch g is preferably 55 of wood and is located between the adjacent

portions of the strip e. In the present instance a reinforcing strip of raw hide h extends across the throat piece.

A maximum of strain occurs at and adjacent the lower portion of the bow, and it has been found that improved results are also attained by applying thin strips I of raw hide to the exterior of the strip d at and immediately above the throat of the frame. Results in balance have been found better when the strips I have not extended to the head of the bow. The last mentioned strips are retained by glue and the catgut B.

If desired rivets j may be employed to assist in binding the bow and throat piece in the usual manner.

The strips f and I are preferably of a width equal to the thickness of the bow. The strip h of raw hide adds to the strength 75 of the structure.

I claim:

1. A tennis racket formed of continuous strips of wood, combined with a strip of raw hide incorporated in the bow throughout its length. 80

2. A tennis racket comprising a plurality of bow strips of wood, a strip of raw hide interposed between the strips, and means for uniting all the strips. 85

3. A tennis racket comprising a plurality of bow strips, a strip of raw hide interposed between the other strips throughout their length, and a net uniting all the strips. 90

4. A tennis racket comprising bow strips of wood, a strip of raw hide interposed between the first mentioned strips throughout their length, a throat piece, and a reinforcing strip of raw hide on the throat piece. 95

5. A tennis racket comprising a bow, a throat piece in the bow, a handle, and reinforcing strips of raw hide upon the exterior only of the bow adjacent the throat piece. 100

6. A tennis racket comprising a bow, a strip of raw hide incorporated in the bow throughout its length, a handle supporting the bow, and strips of raw hide on the exterior only of the lower portions of the bow at each side of the handle.

In testimony whereof I have affixed my signature in presence of two witnesses.

FREDERICK J. BANCROFT.

Witnesses:
